UNITED STATES PATENT OFFICE

2,609,660

RESONATING PULSE JET ENGINE

William L. Tenney, Crystal Bay, Minn., and Charles B. Marks, Las Vegas, Nev.; said Marks assignor to said Tenney

Application February 25, 1946, Serial No. 649,882

12 Claims. (Cl. 60—39.14)

1

This invention relates to pulse jet engines and particularly to small size pulse jet engines suitable for the propulsion of miniature or model airplanes, automobiles, boats and the like, and for furnishing a jet impulse for miniature or toy turbines or similar devices, whatever they might be.

It is an object of the invention to provide a pulse jet engine, particularly of the miniature or model type, which combines utmost simplicity and low cost of manufacture with high efficiency of operation as well as lending itself to incorporation into miniature airplanes, cars, etc., as a structural part thereof. It is also an object of the invention to provide a small pulse jet engine having a very high thrust for its weight and size, capable of being started and operated easily and safely, as well as being extremely simple to assemble and disassemble for servicing and replacement of the valve which constitutes the only moving part. It is a further object of the invention to provide an improved, economical, sturdy and attractive pulse jet engine assembly. It is a particular object of the invention to provide an improved, efficient, very simple and inexpensive valve mechanism for miniature pulse jet engines.

Other and further objects of the invention are those inherent in the apparatus herein illustrated, described and claimed.

The invention is illustrated with reference to the drawings in which:

Figure 1 is a side elevational view, partly in section, showing the external appearance of the jet propulsion unit and an air cooling shroud or part of the model in which the device is incorporated. The shroud or model part is shown in section;

Figure 2 is a fragmentary cross sectional view of the carburetor, valve and starting mechanism, combustion chamber and a fragment of the tail pipe assembly;

Figure 3 is a sectional view taken along the lines 3—3 of Figure 2;

Figure 4 is a fragmentary view, partly in section, showing one type of ignition plug mounting;

Figure 5 is a fragmentary view, partly in section, showing a modified form of attachment between the valve plate intake and combustion chamber, a modified form of fastening for valve, valve stop and fuel jet, and modified forms of valve stop;

Figure 6 is a fragmentary sectional view of a modified form of the invention;

Figure 7 is a fragmentary sectional view of a second modified form of the invention;

2

Figure 8 is a sectional view of the type shown in Figure 3, but showing a modified form of valve plate, valve and valve support;

Figure 9 is a sectional view taken at about the position of section line 9—10 of Figure 2, showing a modified form of construction of the combustion chamber and tail pipe; and

Figure 10 corresponds to Figure 9, showing a second modified form of combustion chamber and tail pipe assembly.

Throughout the drawings corresponding numerals refer to the same parts.

Referring to the drawings, the jet propulsion unit includes a combustion chamber generally designated 10 which is attached to an integral or fabricated converging section 11 which is attached to an integral or fabricated tail pipe, generally designated 12. The combustion chamber is also attached to a carburetor and valve plate unit generally designated 14 which may be covered by a streamlined nose section 9.

Referring to Figure 2 the carburetor and valve plate member 14 has a circular disk portion 15 which is faced so as to present a smooth flat surface at 16. The carburetor and valve plate member 14 has an integral Venturi section 17 which presents a narrow throat at 18 and a bellied out inlet opening 19. The outer edge of the bell is provided with a smooth surface 20 upon which the inturned flange 21 of the streamlined nose piece 9 rests in frictional engagement. The disk portion 15 is provided with a central shoulder 22 and is threaded in the forward direction at 24 and in the rearward direction at 25. Threads 25 receive a threaded ring 26 which is set into the inside of the combustion chamber 10 at its forward end. The ring 26 may be fastened by spot welding, gas welding or any other suitable fastening. The threads 24 likewise serve to support the ring 28 which is likewise set into the rear portion 30 of the streamlined nose section 9 which may be integral with the ring 28 or attached by welding or other suitable means. It may be noted that the front of the unit is the bell-shaped opening 19 of the Venturi section, since in operation the unit moves in the direction of the arrow 32. When the nose section 9 is screwed onto the threads 24, the inturned flange 21 rests against the surface 20 of the venturi 17 and the outer end of the streamlined nose section is thereby solidly supported. The tail pipe section 12 may be made integral with the reducing section 11 or the two may be welded together, if desired, and the reducing section 11 may be made integral or welded to the tail pipe section 12. The

joints between 10 and 11 and between 11 and 12 may be by gas welding, spot welding of the like. In some instances it is feasible to utilize a tube of original diameter 12 and draw it so as to present the joining section 11 and the combustion chamber space 10 or a tube of size 10 may be necked down through the section 11 to the tube section 12.

In Figures 9 and 10 there are illustrated methods of fabrication especially well adapted for the making of the combustion chamber and tube section. In these figures the combustion chamber 10, reducing section 11 and tail piece 12 are made in two symmetrical halves (Figure 9) or in three symmetrical thirds (Figure 10). Thus, the half sections 34 and 35 are provided with flanges 36 and 37 which extend outwardly throughout the length of the combustion chamber 10, the reducing section 11 and the tube section 12. The flanges may be fastened together by means of a rolled lock joint seam or may be attached by gas welding or spot welding or continuous electric welding along the length of the unit. In Figure 10 the same method of construction is used except that the one-third sections 38, 39 and 40 are provided, each section being flanged at its edge so as to provide a point of attachment to the adjacent section. In both Figures 9 and 10 the flanges formed by the juncture of 36 and 37 may serve as cooling fins, stiffeners, and additional mounting points.

In Figure 1 there is illustrated an air shroud generally designated 45 which may, if desired, be shaped as the fuselage of a model airplane, the body of a model car or similar body part into which the unit is fabricated. The air shroud 45 is formed in the shape of a tube which provides an air inlet at 46 and an air outlet at 48. If desired, shroud 45 may be terminated at 49 beyond the termination point 50 of the jet propulsion unit. Thus, the jet emanating from the tube 50 provides a suction effect which induces a flow of cooling air around the jet tube 12 introduced at inlet 46, even when the unit is not in forward motion. Where the assembly 10, 11 and 12 is fabricated without the outwardly extending flanges 36 and 37 of the type shown in Figures 9 and 10, the spacing of the shroud 45 may be provided by means of thin inwardly projecting ribs 52 extending lengthwise of the unit at the front end thereof and by similar projecting ribs 54 at the rear end thereof or by other suitable means. A plurality of these ribs, usually three or four, may be provided in both the front and back and thus adequately support the shroud in spaced relationship around the jet propulsion unit. The attachment of the shroud to the unit may be by means of pins or screws 55 which are preferably recessed into the metal of shroud 45 and passed into the flange 22 of the valve plate 14, or shroud attachment may be made to an integral part of a model airplane, car, etc. which replaces section 9, or by other suitable means. The shroud 45 may also be dispensed with altogether for purposes of economy and light weight, and attachment of accessories, wings, axles, etc. be made directly to sections 10, 11 and 12 and also to threads 24, if desired. Where the combustion chamber and tail pipe include the flanges 36 and 37 of the type shown in Figures 9 and 10, the spacing and supporting members 52 and 54 may be omitted since the ribs in themselves will provide the necessary spacing and support.

Referring to Figures 2 and 3, the valve plate

14 is drilled or cast with a ring of inwardly and forwardly converging holes 56. The holes 56 extend at an angle to the center line of the unit and in converging towards each other, intersect and define a cone 58. The cone is, of course, supported at its rearward end by the web spacing 59 between the holes 56 in the valve face 16. If desired, the cone 58 may be finished so as to provide a smooth circular surface at its forward portion beyond the point of intersection of the several holes 56, or the flutes formed by the holes 56 may be permitted to remain. It is to be understood, of course, that the holes 56 may be cast, and in such instance the surface of cone 58 may be smooth or fluted as determined by the molds and cones of the casting. The valve plate 14 and cone 58 are drilled centrally at 62 and threaded to receive the cap screw 63 which serves to attach a valve backstop 64 and a valve 65. The valve 65 is shown out of scale in the drawings, but it is actually a thin, flat, springy member. For this purpose high carbon blue spring steel serves adequately. The valve 65 is of generally circular shape and is apertured at the center 67 so as to permit the clamping cap screw 63 to pass therethrough. Outside of the aperture there is a small annular area 66 and beyond this the valve disk is slotted or cut as indicated at 68. The width of the slot 68 is determined largely by the spacing of the holes 56 in the valve plate, and since these are desirably set close together so as to provide a maximum port area, the slots 68 are accordingly usually very narrow. The radial slots 68 serve to form the valve disk into a plurality of petals indicated at 69. The petals are identical or nearly identical and are shaped off at their outer ends as indicated at 70. If desired, the outer ends may be rounded.

In practice we have found that blue tempered spring steel stock .006 inch in thickness gives excellent results, although stock of somewhat thinner or thicker dimension may be used.

The valve backstop 64 has a convex forward surface which has a flat central area 72 having a diameter preferably slightly larger than the central uncut area 66 of the valve. Therefore, when the valve backstop 64 is drawn tightly down against the valve plate with the valve 65 therebetween, each of the petals 69 is in effect separately clamped. The shape of the rear surface 74 of the valve backstop is of relatively little importance and is illustrated in Figure 2 as slightly dished. As will presently appear in the description of Figures 5, 6 and 7, the shape of this rear surface may be quite widely varied without disadvantageously affecting the operation of the device. The front curved surface 75 of the valve backstop 64 is, however, important since it serves to support the valve at its maximum deflection. The front surface 75 of the valve stop is shaped so as to provide a limit and support for the valve at its maximum deflection during operation and so as to provide support for the valve from the point of clamping of the valve radially outward to the edge of the valve backstop. The valve may, if desired, extend somewhat beyond the valve backstop in order to allow air flow between the shaped ends 70 of the valve petals when the valve is at or near its point of maximum deflection. By shaping the valve stop correctly, the form and extent of valve deflection may be controlled so as materially to increase valve life and achieve even seating of the valve on the valve plate surface 16.

In assembling the valve 65 in place on the valve plate 14, it is preferably located against turning by two pins 11 set approximately diametrically opposite each other. The backstop 64 is then set on and is clamped down by screws 63. Any turning of the valve 65 with reference to plate 14 is resisted by pins 11. The pins are then removed and the unit is ready for operation.

Ignition is required only during the starting of the device, this being provided by means of a usual model gasoline engine spark plug 78 which is threaded into the boss 79 on the tapered section 11. If desired, the valve plate may be recessed as shown at 80 in Figure 4, and the spark plug set in as indicated in this figure. Suitable apertures are provided in the shroud 45 (or in the nose section 9 when the spark plug is located as in Figure 4), so as to allow temporary attachment of a spark ignition wire.

Introduction of the fuel into the venturi is provided by means of the fuel jet pipe 82 which is threaded at 83 so as to fit into the hole 62 in cone 58. The pipe 82 is preferably made from solid bar material and has a conical flange 84 shaped so as to fit up against the flat face 85 of the cone 58 and to continue the conical surface to the diameter of the rod 82. The rod 82 is drilled out at 87 to the position of holes 88 which are cross drilled through the rod and serve as fuel metering orifices and spray nozzles. The rod is provided with a ball-shaped protuberance 90. Forwardly of the ball 90 there is provided a gusset plate 92 to which an air injecting pipe 93 is attached so as to have a slight clearance from the ball 90 and terminates at about position 94. The pipe 93 is used only in starting. At this time an air hose 95 is attached. The air blast through the tube 93 scrubs over the holes 88 in each side of the rod, thereby drawing gasoline or other fuel from the fuel supply tank and ejecting it from holes 88 in a spray. The blast of air and fuel then continues through the holes 56 and lifts the valves sufficiently so as to permit the combustible mixture to enter the combustion chamber 10 where it is ignited by the spark plug 78. As combustion starts the valve petals 69 close against the seat 16 due to their own resiliency and also due to the force of the explosion. The explosion sets up a blast through the tail pipe 12 and the blast in traveling down the tail pipe causes an injector suction which draws fresh air through the venturi 17. The flow of air through the venturi 17 is sufficient to draw the fuel out of the jet holes 88 and provide a combustible mixture. This combustible mixture then passes through the valve ports 56 into combustion chamber 10, is ignited, and the cycle repeats with extreme rapidity. The starting air tube 95 is then removed and the ignition wire likewise disconnected. Ignition is automatic after the device is started. The device is then freed and the force of the jet which comprises the propelling force drives the device very rapidly.

Particular attention is invited to certain features of construction and operation set forth above. First, the valve consists of but one piece, which can be made on a punch press. In spite of the extreme simplicity of this valve, it is efficient in opening a large effective port area, since it is clamped at its center and lifts axially away from its center; the maximum lift is at its outer periphery, and hence a large effective valve area is opened. In other types of miniature pulse jet engine valves of which we have knowledge, the valves are clamped at or near the outer diametral

limits of the combustion chamber and the maximum lift is at or near the center of the combustion chamber; hence, only a small effective valve port area may be opened. Further, these valves are made up of several pieces and are fastened in several places, whereas with our valve construction only one fastening screw is required. In order to change our valve only one screw need be removed.

Likewise, our valve stop is made up of only one piece and fastened by one screw which also serves to fasten the valve. Since this stop is merely a disk with a central hole and a convex surface on one side, it may be made with great ease on automatic screw machines or on punch presses.

The valve seating surface is flat and lies in one plane only, lending itself admirably to low cost manufacture. Should the seat become in any way damaged, it can be resurfaced by simply lapping it against a piece of emery cloth placed over a flat surface.

The fuel inlet jet is of simplest construction and is fastened in the same hole as the valve and stop clamping screw.

The system of starting and fuel supply of the present invention has outstanding advantages in safety, low cost and simplicity over other systems of which we have knowledge. In our system the fuel tank (not illustrated) is located below the lowest port of the combustion chamber and fuel is drawn through the fuel line (82 of Figures 1 and 2; 118 of Figure 6 or 196 of Figure 7) by the negative pressure induced by the air flow through the Venturi intake tube (17 of Figures 1 and 3) or, in case of starting, by the suction effect at the fuel nozzle, produced by the air blast from the starting air tube. This prevents flooding and dangerous operations that were common in prior jet engines. In one such prior system a pressurized fuel tank was employed. In starting, the tank is pressurized from the starting air source and when the unit is in operation pressure is supplied from a controlled leak in the combustion chamber. Aside from being complex and expensive to manufacture, this system introduces a fire hazard which is objectionable in apparatus of this type.

In our system the angle of the starting air tube 93 in relation to the jet rod 82 is adjusted and set so that a combustible fuel-air mixture is supplied over a wide range of air pressures. Thus, whenever air under pressure for starting is supplied through tube 93 a combustible mixture is fed to the combustion chamber; it is impossible to supply an over-rich mixture. With the pressurized tank system of the prior art, or with gravity feed systems, over-rich incombustible mixtures are often supplied, resulting in the collection of liquid fuel in the combustion chamber. When a combustible mixture is subsequently supplied the liquid fuel is blown out the tail pipe as a sheet of flame. With our system, this action does not occur.

We have also experimented with gravity feed systems which though inexpensive have proven dangerous both in starting and in operation.

We therefore prefer the suction feed system as illustrated, although the use of other types of fuel feeding systems in our device is not excluded.

The following exemplary construction may be cited as an illustrative embodiment of the invention but should not be considered as a limitation thereon since dimensions may be varied pro-

portionally within limits while maintaining good operation.

Example I

The tail pipe is 15 inches long, $1\frac{3}{8}$ inches diameter and approximately .020 inch thick. It is constructed of stainless steel. The converging section 11 is $2\frac{1}{2}$ inches long having a minimum diameter the same as the tail pipe and a maximum diameter the same as the combustion chamber, i. e. $2\frac{1}{2}$ inches. The combustion chamber is $1\frac{5}{8}$ inches long and $2\frac{1}{2}$ inches in diameter. The valve plate-venturi is approximately $2\frac{1}{4}$ inches long and is made of aluminum. The valve plate is drilled with 16 holes, $\frac{1}{4}$ inch in diameter drilled on a circle $1\frac{1}{8}$ inches in diameter and converging into a venturi having a throat diameter of 1 inch. Since the holes 56 are at an angle their intersection with the face 16 of the valve plate is not quite circular. The distance from the outer edge of one hole to the outer edge of the diametrically opposite hole in the circle of valve holes is $2\frac{1}{8}$ inches. The valve 65 is made of blue tempered spring steel stock .006 inch thick and has an overall diameter of $2\frac{5}{8}$ inches. The slots between adjacent petals 69 of the valve are approximately $\frac{1}{2}$ inch at their widest part and extend to within .25 inch of the center of the circle. The center hole for attaching the valve is sufficient to receive a $\frac{1}{4}$ inch screw and the uncut annular area 66, Figure 3, is approximately .125 inch in width. The valve backstop was likewise drilled to receive a $\frac{1}{4}$ inch screw 63 and has a flat area of contact against the valve of approximately .550 inch diameter. The outer diameter of the valve backstop is 1.6 inches and the curvature thereof is such as to allow a valve lift of the tip of the valve of approximately $\frac{1}{4}$ inch, it being noted that the tip of the valve extends substantially beyond the outer diameter of the valve backstop. The fuel orifices 88 are reamed with a #58 drill, and the starting air inlet pipe is .080 inch inside diameter. The mechanism so constructed produces in excess of four pounds static thrust with no ram air supplied. Starting was easily accomplished by connecting an air supply hose temporarily to the starting air pipe 93. Approximately 50 pounds starting air pressure is needed for an easy start, although starting may be accomplished at pressures as low as 35 pounds and lower under favorable circumstances. The combustion is clean and leaves practically no residue. The cycle frequency is 230 cycles per second as determined by an oscillograph with vibration pick-up. The valve life is greatly in excess of that required for miniature applications, for example in model airplanes.

Example II

A combustion chamber 4 inches in diameter and having an overall length, including the tapered section 11, of approximately 4 inches, tail pipe 2 inches in diameter and 30 inches long was used. The valve plate was made of magnesium and drilled as described in Example I, with 16 holes of $\frac{1}{4}$ inch drilled to converge into a venturi having an internal diameter of 1.33 inches. The diameter from the center of one valve port to the center of the diametrically opposite valve port is approximately 2.3 inches and the diameter from the outer edge of one port to the outer edge of the diametrically opposite port is approximately 2.75 inches. The valve was made of blue spring steel stock .010 inch thick and had an overall diameter of 2.8 inches. The diameter of the uncut area 66 (Figure 3) and the diameter of the

flat area of contact of the valve backstop 64 were both .75 inch. The valve lifted approximately .32 inch as measured from the surface of the valve plate to the tip of the valve spring when lifted to its maximum point. It may be noted in passing that the lines of contact marked in operation by the valve against the valve backstop show clearly that in operation the valve lifts until it lies entirely in contact with the curved surface of the valve backstop plate. In this instance the diameter of the valve backstop plate is approximately 2.4 inches. This unit developed in excess of seven pounds static thrust with no ram air.

Referring to Figure 6 there is illustrated a modified form of the invention wherein the principal variation from the device shown in Figures 1-5 is in the shape of the valve plate. In Figure 6 the valve plate generally designated 100 is provided with a flat central area 101 and a conical peripheral area 102 through which the entrance holes 103 extend. In this instance, as in the device shown in Figures 2 and 3, a plurality of holes 103 are drilled through the valve plate in a manner so as to converge into the Venturi section generally designated 105, and thus form a conical center 106 reaching into the throat of the venturi. The valve has a flat central area 108 and this portion of the valve is held in contact with the flat central area 101 of the valve plate by means of the valve backstop generally designated 110 which likewise has a flat central area 111 and is held in place by means of the cap screw 112. The valve is slotted to just beyond the bend 113 so as to form individual outwardly protruding petal-shaped blades 115 which are oriented so as to cover each of the valve ports formed by the holes 103. The petal-shaped blades 115 are substantially flat, but may be preformed to the shape of the conical surface 102. It may be noted, however, that due to the small diameter of the holes 103 as compared with the diameter of the conical surface 102 through which they protrude, it is relatively immaterial whether or not the valve blade is preformed since over the area of the valve port hole a flat blade serves to provide sufficiently tight valve closure. The valve backstop 110 has a curved surface 114 shaped so as to provide adequate support for the valve in its lifted position, as shown in dotted lines at 116. Fuel is introduced by means of the fuel inlet pipe 118 which is brazed or soldered to the plate 119, the latter in turn being pinned or riveted to the entrance 120 of the venturi. To the tube 118 there is attached a small gusset plate 122 which in turn serves to support the starting air inlet pipe 123. For starting air supply tube 124 is attached and air under pressure is applied as previously described. This serves to draw fuel from the opening 125 of the pipe 118 and to move the air fuel mixture through the holes 103 and thence against the petal-shaped valve blades 115 which are lifted off their seats on the surface 102 and fuel-air mixture is introduced in the combustion chamber 130 where the starting combustion is initiated by the spark plug 131.

In Figure 6 the valve plate body 100 is provided with outwardly converging flange 132 having surfaces 133 and 134. The wall 136 of the combustion chamber is flanged out at 137 and the rear surface 138 of the cowling 140 is likewise flanged out so that the two lie in contact with the slanting surfaces 133 and 134. A clamping ring 142, having corresponding slanting surfaces and provided with a screw device 143 at one point in its diameter, is then placed on and the

screw 143 tightened so as to provide a hoop tension which accordingly draws the cowling and the combustion chamber firmly into contact with the surfaces of the flange 132.

The conical valve seat illustrated in Figure 6 is of interest in that it offers a more efficient valving arrangement than that illustrated in Figures 1 and 3, without additional complication or expense, except that involved in the manufacture of the conical seat itself, and this need be but very slight under mass production methods. With the conical seat the diameter of the valve port circle may be increased in relation to the combustion chamber diameter without reducing the air flow, since the direction of flow over the valve tips is more nearly parallel to the combustion chamber wall than with the flat seat arrangement. This fact in itself permits of a greater area of holes 103 for a given combustion chamber diameter. In addition, the shaping of the holes 103 at their intersection with the conical surface 102, plus the direction of air flow in relation to valve, valve backstop and combustion chamber, produces a higher coefficient of discharge per unit area of holes 103 than exists with the flat seat arrangement.

The conical seat cannot be resurfaced as simply as the flat seat, however. Provision of a hard seat surface by plating, anodizing or other suitable means eliminates any need for resurfacing, but at additional cost.

In the modification shown in Figure 7 the valve plate generally designated 150 is separated from the Venturi body 151 along the line 153 for convenience in manufacture. Thus, the plate 150 when removed can easily be die cast or machined and the Venturi body 151 is likewise more readily machined or cast. The valve plate is recessed into the threaded shoulder 154 of the Venturi body and is held in place by the inturned flange 156 of the screw ring 158 which is set into the forward end of the combustion chamber. In this instance the wall 160 of the combustion chamber is flanged out slightly so as to present a shoulder at 161 against which the ring 158 seats and the protruding end of the wall is turned in at 163 so that when the combustion chamber is drawn down the inturned portion 163 of the combustion chamber seats tightly against a gasket at 165, the gasket in turn being seated against the shoulder 166. The combustion chamber 170 is necked down at 171 and joined to the tail pipe 172, as previously described.

The valve plate 150 is provided in this instance with a plurality of cast in openings 175 which terminate normal to the flat surface 178 of the valve plate. Thus, for a short distance, as indicated at 179, the opening 175 is of the uniform shape shown at 175 in Figure 7. Hence, the valve plate 150 may be re-faced without changing the position of the valve ports. The ports 175 have the shape shown in Figure 8 and each of the valve petals 181 is shaped so as to provide a substantially constant overlap around the edge of the port except at the inner part where the valve petal extends to the uncut portion 182. The valve backstop 190 is likewise cut out in petal-shaped formation so as to provide a free space 192 between adjacent petals 193 of the valve backstop. In this way, as the valve petals 181 lift off the ports 175, the flow of fuel-air mixture through the port is permitted not only around the tip or outer end of the valve, but also around each of its side edges, and flow continues up around the petal-shaped backstop fingers 193 through the intervening spaces 192.

The valve backstop is in this instance held in place by the fuel jet rod 196 which extends through the hole 198A and is threaded at its inner end to receive nut 197 which thus serves to clamp the valve backstop 190 and valve 181 in place. The outer end of the fuel jet rod 196 is drilled so as to provide a fuel passage and terminates in fuel jet openings at cross bore 198. The fuel jet rod 196 serves to support gusset plate 199 which in turn serves to support the air injecting tube 200 for providing the starting air supply. The cowling 201 is provided with an internally threaded ring 202 which is soldered or welded in place or otherwise suitably fastened, the cowling being thus attached by screwing up on the threads 203, as previously described.

In Figure 2 or in Figure 7 the jet propulsion unit may be mounted by removing the cowling 9 (of Figure 2) or cowling 201 (of Figure 7) and by inserting the jet propulsion device through a mounting ring or aperture of the propelled device (not illustrated) having a diameter sufficient to receive the threaded portion 24 or 203. The cowling is then screwed into place and thus serves to clamp the device in place on the model or vehicle to which it is to be applied. This serves as a ready mounting for the device. In Figure 6 the mounting bracket may readily be attached to the hoop 142 either at the screw portion 143 or elsewhere around the hoop.

In Figure 5 there is shown a modified form of the invention wherein the valve backstop 206 is threaded so as to screw on the inwardly protruding threaded end 196B of the fuel inlet rod 196. The surface of the valve backstop facing the combustion zone may be shaped as desired. In this modification also, the side wall 200 is flanged in at 201 over the threaded internal ring 202 which is fastened against turning by dimpling, crimping, spot welding, silver-solder, or the like. As the combustion chamber and ring 202 are turned down on threads 203, the ring clamps the flange 201 firmly against flange 204.

It will be noted that in Figures 5, 6 and 7 the valve backstop diameter is made equal to or greater than the valve disk diameter. This is done in order that, if desired, the valve stop may protect the valve from the major heat and force of combustion and act to protect and cool the valve.

As many apparently widely different embodiments of this invention may be made without departing from the spirit and scope thereof, it is to be understood that we do not limit ourselves to the specific embodiments herein except as defined by the appended claims.

What we claim is:

1. In a resonant pulse jet apparatus, an inlet port and valve unit adapted to be secured at one end of a combustion chamber, said unit comprising means forming a passage having an air inlet opening, said passage having a tapering cross section defining a Venturi throat passage and then being branched into a plurality of annularly arranged openings terminating in ports on the face of said unit, valve means including a segmental flexible valve member with the segments thereof overlying said port openings, means carried by said unit for supporting said valve means with the segments thereof exposed for flexing to control the flow of fuel and air through said port openings, and means located at said Venturi throat for supplying fuel in metered relation into the inflowing air in said passage for vaporization thereof for combustion with resultant cooling of said unit and valve means.

11

2. In a resonant pulse jet apparatus, an inlet port and valve unit adapted to be secured at one end of a combustion chamber, said unit comprising means forming a passage having an air inlet opening, said passage having a portion of tapering cross section defining a centrally located throat and another portion extending outwardly defining a plurality of annularly arranged openings terminating in ports, valve means including a segmental flexible valve member with the segments thereof overlying said port openings, means carried by said unit for supporting said valve means with the segments thereof overlying said port openings, and means located at said throat for admitting fuel in metered relation into the inflowing air in said passage for vaporization thereof for combustion with resultant cooling of said unit and valve means.

3. In a resonant pulse jet apparatus, an inlet port and valve unit adapted to be secured at one end of a combustion chamber, said unit comprising means forming a passage having an air inlet opening, said passage having a portion of tapering cross section defining a centrally located throat and another portion extending outwardly defining a plurality of annularly arranged openings terminating in ports, valve means including a segmental flexible valve member with the segments thereof overlying said port openings, means carried by said unit for supporting said valve means with the segments thereof overlying said port openings, means located at said throat for admitting fuel in metered relation into the inflowing air in said passage for vaporization thereof for combustion with resultant cooling of said unit and valve means, and an auxiliary air supply tube for supplying starting air into said throat for producing an ignitable mixture of fuel and air in predetermined correlated proportion.

4. In a resonant pulse jet apparatus, an inlet port and valve unit adapted to be secured at one end of a combustion chamber, said unit comprising means forming a passage having an air inlet opening, said passage having a portion of tapering cross section defining a centrally located throat and another portion extending outwardly defining a plurality of annularly arranged openings terminating in ports, valve means including a segmental flexible valve member with the segments thereof overlying said port openings, means carried by said unit for supporting said valve means with the segments thereof overlying said port openings, means located at said throat for admitting fuel in metered relation into the inflowing air in said passage for vaporization thereof for combustion with resultant cooling of said unit and valve means, and means for supporting said auxiliary air supply tube on said unit at an acute angle to the axis of the unit.

5. In a resonant pulse jet apparatus, an inlet port and valve unit adapted to be secured at one end of a combustion chamber, said unit comprising means forming a passage having an air inlet opening, said passage having a portion of tapering cross section defining a centrally located throat and another portion extending outwardly defining a plurality of annularly arranged openings terminating in ports, valve means including a segmental flexible valve member with the segments thereof overlying said port openings, means carried by said unit for supporting said valve means with the segments thereof overlying said port openings, and means located at said throat for admitting fuel in metered relation into the inflowing air in said passage for vaporization

12

thereof for combustion with resultant cooling of said unit and valve means, said fuel supply means including a fuel supply tube having an outlet orifice within said passage.

5 6. In a resonant pulse jet apparatus, an inlet port and valve unit adapted to be secured at one end of a combustion chamber, said unit comprising means forming a passage having an air inlet opening, said passage having a portion of tapering cross section defining a centrally located throat and another portion extending outwardly defining a plurality of annularly arranged openings terminating in ports, valve means including a segmental flexible valve member with the segments thereof overlying said port openings, means carried by said unit for supporting said valve means with the segments thereof overlying said port openings, means located at said throat for admitting fuel in metered relation into the inflowing air in said passage for vaporization thereof for combustion with resultant cooling of said unit and valve means, a protuberance on said tube ahead of said outlet orifice, and an auxiliary air supply tube terminating adjacent said protuberance for supplying starting air into said throat.

20 7. In a resonant pulse jet apparatus, an inlet port and valve unit adapted to be secured at one end of a combustion chamber, said unit comprising means forming a passage having an air inlet opening, said passage having a tapering cross section defining a centrally located throat, a generally cone-shaped member with its apex adjacent said throat and defining an annular portion having a plurality of annularly arranged openings terminating in ports on the face of said unit, valve means including a segmental flexible valve member with the segments thereof overlying said port openings, means carried by said unit for supporting said valve means with the segments thereof exposed for flexing to control the flow of fuel and air through said port openings, and fuel supply means located at said throat and having an outlet orifice for supplying fuel into the air stream traveling through said passage for vaporization of the fuel and concurrent cooling of said passage and valve means.

30 8. In a jet apparatus, an inlet port and valve unit adapted to be supported at one end of a combustion chamber, said unit comprising an inlet member defining a flow passage of generally 35 Venturi shape, means for detachably mounting said member in position adjacent the end of said combustion chamber, means carried by said member for introducing fuel into the air stream substantially in the throat of said venturi, means forming annularly arranged passages extending from said throat to a series of inlet ports for introduction of the mixture of fuel and air, a segmental valve member having its radially outer portions overlying said inlet ports, and a central support for removably mounting said valve member upon said inlet member providing for ready removal and replacement of said valve member upon removal of said unit from operative position.

40 9. In a jet apparatus, an inlet port and valve unit adapted to be supported at one end of a combustion chamber, said unit comprising an inlet member defining a flow passage of generally 45 Venturi shape, means for detachably mounting said member in position adjacent the end of said combustion chamber, means carried by said member for introducing fuel into the air stream substantially in the throat of said venturi, means forming annularly arranged passages extending from said throat to a series of inlet ports for in-

introduction of the mixture of fuel and air, a generally cone-shaped member supported in said unit with its apex extending toward said throat defining annularly arranged passage means extending from said throat to a series of inlet ports for introduction of the mixture of fuel and air, a segmental valve member having its radially outer portions overlying said inlet ports, and a central support for removably mounting said valve member upon said inlet member providing for ready removal and replacement of said valve member upon removal of said unit from operative position.

10. In a jet apparatus, an inlet port and valve unit adapted to be supported at one end of a combustion chamber, said unit comprising an inlet member defining a flow passage of generally Venturi shape, means for detachably mounting said member in position adjacent the end of said combustion chamber, means carried by said member for introducing fuel into the air stream substantially in the throat of said venturi, means forming annularly arranged passages extending from said throat to a series of inlet ports for introduction of the mixture of fuel and air, a generally cone-shaped member supported in said unit with its apex extending toward said throat defining annularly arranged passage means extending from said throat to a series of inlet ports for introduction of the mixture of fuel and air, a segmental valve member having its radially outer portions overlying said inlet ports, a central support for removably mounting said valve member upon said inlet member providing for ready removal and replacement of said valve member upon removal of said unit from operative position, and a valve backstop mounted in said cone-shaped member for securing said valve member centrally to said unit and providing for ready removal therefrom.

11. In a jet apparatus, an inlet port and valve unit adapted to be supported at one end of a combustion chamber, said unit comprising an inlet member defining a flow passage of generally Venturi shape, means for detachably mounting said member in position adjacent the end of said combustion chamber, means carried by said member for introducing fuel into the air stream substantially in the throat of said venturi, means forming annularly arranged passages extending from said throat to a series of inlet ports for introduction of the mixture of fuel and air, a generally cone-shaped member supported in said unit with its apex extending toward said throat defining annularly arranged passage means extending from said throat to a series of inlet ports for introduction of the mixture of fuel and air, a segmental valve member having its radially outer portions overlying said inlet ports, a central support for removably mounting said valve member upon said inlet member providing for ready removal and replacement of said valve member

upon removal of said unit from operative position, said fuel introducing means including a fuel supply tube having an outlet orifice, and means for supporting said tube upon said cone-shaped member with said orifice in said throat of said passage.

12. In a jet apparatus, an inlet port and valve unit adapted to be supported at one end of a combustion chamber, said unit comprising an inlet member defining a flow passage of generally Venturi shape, means for detachably mounting said member in position adjacent the end of said combustion chamber, means carried by said member for introducing fuel into the air stream substantially in the throat of said venturi, means forming annularly arranged passages extending from said throat to a series of inlet ports for introduction of the mixture of fuel and air, a generally cone-shaped member supported in said unit with its apex extending toward said throat defining annularly arranged passage means extending from said throat to a series of inlet ports for introduction of the mixture of fuel and air, a segmental valve member having its radially outer portions overlying said inlet ports, a central support for removably mounting said valve member upon said inlet member providing for ready removal and replacement of said valve member upon removal of said unit from operative position, said fuel introducing means including a fuel supply tube having an outlet orifice, means for supporting said tube upon said cone-shaped member with said orifice in said throat of said passage, an auxiliary air supply tube for discharging air for starting across said fuel orifice, and means for supporting said auxiliary air supply tube in predetermined accurate relation on said fuel supply tube.

40 WILLIAM L. TENNEY.
